UNITED STATES PATENT OFFICE.

ARTHUR M. HOOD, OF INDIANAPOLIS, INDIANA.

EXCAVATOR.

Application filed January 8, 1925. Serial No. 1,138.

The object of my invention is to produce an excavator of the dipper type in which the digging swing and forward crowd is accomplished by a single cable and the 5 turn lift and resistance to crowd is accomplished by an independent coordinated lifting means.

The accompanying drawings illustrate my invention. Fig. 1 is a side elevation 10 largely diagrammatic in character, illustrating an embodiment of my invention and Figs. 2 and 3 are diagrammatic illustrations of equivalent rope reavings.

In Fig. 1 10 indicates a suitable supporting structure as, for instance, a truck which may be motorized, the truck being provided 15 with a turn table 11, an anchorage mast 12 and a motor 13 equipped with two winding drums 14 and 15, all being of common 20 construction and the axis of the turn table 11 being vertically beneath the upper end of the anchorage mast 12. The above described construction may be of any ordinary well-known character.

25 Supported upon turn table 11 is an upwardly and outwardly extended boom 16 supported at a desired inclination from the upper end of mast 12 by a stretcher bar 17 and suspension cables 18. Mounted on 30 the outer end of boom 16 is a sheave shaft 20 upon which is journaled a sheave 21.

35 Boom 16 is conveniently formed of two parallel laterally spaced channels so that the sheave 21 may lie between the channels as indicated.

Journaled upon shaft 20 is a swinging yoke 23 which forms a guide for a dipper handle 24 which is conveniently made of 40 two parallel spaced channels, one lying upon each side of the sheave 21 and lying between the channels of boom 16, the arrangement being such that the dipper handle 24 is freely slideable in yoke 23 and 45 is swingable about shaft 20 as an axis. The outer end of the dipper handle 24 carries a dipper 25 of any well-known form, the details of which form no part of my present invention.

50 The upward retracting movement of the dipper handle is accomplished by a pull back cable 26 in the present instance anchored to the outer end of the dipper handle. Of course it will be understood 55 that cable 26 may be associated with the dipper handle 24 in any desired manner so

that a pull on the cable will serve to shift the dipper handle longitudinally inwardly. Cable 26 passes over a sheave 27 journaled on boom 16, over a sheave 28 journaled at 60 the lower end of the boom 16, thence down through table 11 at its axis and around sheave 29 to the winding drum 14.

For the purpose of swinging the dipper 25 upwardly and crowding the dipper handle 24 outwardly, I provide a cable 30 anchored at one end to the inner end of the dipper handle, passing from thence rearwardly around the sheave of a snatch block 31 carried at the outer end of the yoke 32 pivoted at 33 upon boom 16, thence forwardly around sheave 21, thence around sheave 34 at the inner end of dipper handle 24 and thence to a yoke 35 anchored conveniently upon shaft 20. Anchored upon the outer 75 end of yoke 32 is the lifting cable 36 which passes down over a sheave 37, co-axial with sheave 28, thence down through the turn table and around a sheave 38 co-axial with the sheave 29 and thence to the winding 80 drum 15.

A pull upon cable 36 will act upon cable 30 to simultaneously swing the dipper 25 upwardly and crowd the dipper handle 24 outwardly, the extent of the crowding 85 movement being determined by the extent to which cable 26 is released or held against movement.

In Fig. 2 the cable 30 is anchored at one end to the inner end of the dipper handle, 90 passing thence to and around snatch block 31, thence around sheave 21 to and around sheave 34, thence around sheave 21' co-axial with sheave 21, and thence to an anchorage 95 at the inner end of the handle.

In Fig. 3 the cable 30 is anchored at one end to the snatch block 31, passes from thence to and around a sheave 34' co-axial with sheave 34, thence to and around the sheave of snatch block 31, thence to sheave 100 21, thence to and around sheave 34 and thence to an anchorage on shaft 20.

It will be readily understood that an almost infinite variety of reavings of the cable 30 may be utilized without departing 105 from my invention.

I claim as my invention:

1. An excavator comprising a boom, a dipper handle slidably and swingably mounted upon said boom, a lifting cable 110 anchored upon the boom and passing from thence around a sheave on the inner end of

the dipper handle, thence around a sheave on the boom, thence around a snatch block and thence to an anchorage on the inner end of the dipper handle, and a connection 5 between said snatch block and winding mechanism.

2. An excavator comprising a boom, a dipper handle slidably and swingably mounted upon said boom, a lifting cable 10 anchored upon the boom and passing from thence around a sheave on the inner end of the dipper handle, thence around a sheave on the boom, thence around a snatch block supported upon the boom and thence to an 15 anchorage on the inner end of the dipper handle, and a connection between said snatch block and winding mechanism.

3. An excavator comprising a handled dipper, a support on which said handle is 20 slidably and swingably mounted, a cable having one end anchored on the support the other end associated with one end of the handle and an intermediate bight in end thrust engagement with the handle, a 25 snatch block engaging an intermediate portion of said cable and supported on said support, means for shifting said snatch block, and means for resisting the end thrust of said bight.

30 4. An excavator comprising a handled dipper, a support on which said handle is slidably and swingably mounted, a cable hav-

ing one end anchored on the support, the other end associated with one end of the handle and an intermediate bight in end thrust engagement with the handle, a snatch block engaging an intermediate portion of said cable, means for shifting said snatch block, and means for resisting the end thrust of said bight.

35 5. An excavator comprising a handled dipper, a support on which said handle is slidably and swingably mounted, a cable associated with said support and with said handle at two points to exert an end thrust 40 and a swing thereon, a snatch block engaging an intermediate portion of said cable, means for shifting said snatch block, and means for resisting the aforesaid end thrust.

6. An excavator comprising a handled dipper, a support on which said handle is slidably and swingably mounted, a cable associated with said support and at two points in its length with said handle at one end thereof to exert end thrust and a swing 45 thereon, a snatch block engaging an intermediate portion of said cable, means for shifting said snatch block, and means for resisting the aforesaid end thrust.

50 In witness whereof, I have hereunto set 55 my hand at Indianapolis, Indiana, this 6th day of January, A. D. one thousand nine hundred and twenty five.

ARTHUR M. HOOD.
